LOOSE HAIR COLLECTING ATTACHMENT FOR FUR SEWING MACHINE

Fred L. Olday, Box 1255, Scranton, Pa. 18501

Filed Feb. 16, 1973, Ser. No. 333,390

Term of patent 14 years

Int. Cl. D15—06

U.S. Cl. D70—2 B

FIG. 1.

FIG. 2.

FIG. 3.

FIG. 4.

FIG. 5.

FIG. 6.

FIG. 7.

FIG. 1 is a perspective side view of a loose hair collecting attachment for a fur sewing machine showing my new design;

FIG. 2 is a perspective view of the opposite side thereto;

FIG. 3 is a top plan view thereof;

FIG. 4 is a front elevational view;

FIG. 5 is a back elevational view;

FIG. 6 is a cross-sectional view taken on the line 6-6 of FIG. 4; and

FIG. 7 is a bottom plan view.

I claim:

The ornamental design for a loose hair collecting attachment for fur sewing machine, as shown.
